US0D1085796S

(12) **United States Design Patent** (10) **Patent No.:** **US D1,085,796 S**
(45) **Date of Patent:** **** Jul. 29, 2025**

(54) **GAS COOKTOP**

(71) Applicant: **LG ELECTRONICS INC.**, Seoul (KR)

(72) Inventors: **Sangwoo Kim**, Seoul (KR); **Inhyeuk Choi**, Seoul (KR); **Hongsik Kwon**, Seoul (KR); **Inhwan Ryu**, Seoul (KR)

(73) Assignee: **LG ELECTRONICS INC.**, Seoul (KR)

(**) Term: **15 Years**

(21) Appl. No.: **35/520,998**

(22) Filed: **May 23, 2023**

(80) **Hague Agreement Data**

Int. Filing Date: **May 23, 2023**
Int. Reg. No.: **DM/229473**
Int. Reg. Date: **May 23, 2023**
Int. Reg. Pub. Date: **May 24, 2024**

(30) **Foreign Application Priority Data**

(57) **CLAIM**

The ornamental design for a gas cooktop as shown and described.

DESCRIPTION

1. Gas Cooktop
- 1.1 : Perspective
- 1.2 : Front
- 1.3 : Back
- 1.4 : Left
- 1.5 : Right
- 1.6 : Top
- 1.7 : Bottom
- 1.8 : Exploded

Reproduction 1.8 shows a state of the griddle disassembled from the cooktop body; the broken lines shown in the reproductions depict portions of the gas cooktop that form no part of the claimed design.

1 Claim, 8 Drawing Sheets
